UNITED STATES PATENT OFFICE

168,767

POWER MOWER

Anthony Sarlo, Fort Myers, Fla.

Application April 5, 1951, Serial No. 14,721

Term of patent 14 years

(Cl. D40—1)

To all whom it may concern:

Be it known that I, Anthony Sarlo, a citizen of the United States, residing at Fort Myers, in the county of Lee and State of Florida, have invented a new, original, and ornamental Design for a Power Mower, of which the following is a specification, reference being had to the accompanying drawings, forming part thereof.

Figure 1 is a front elevation of a power mower, showing my new design.

Figure 2 is a top plan view thereof.

Figure 3 is a side elevation, and

Figure 4 is a perspective view of the underside of the platform of the power mower.

I claim:

The ornamental design for a power mower, substantially as shown.

ANTHONY SARLO.
